AMOS W. MERRITT, OF SCITUATE, MASSACHUSETTS

Letters Patent No. 87,788, dated March 16, 1869.

IMPROVEMENT IN LASTS.

The Schedule referred to in these Letters Patent and making part of the same.

To all whom it may concern:

Be it known that I, AMOS W. MERRITT, of Scituate, in the county of Plymouth, and State of Massachusetts, have invented certain Improvements in Lasts, of which the following is a full, clear, and exact description, reference being had to the accompanying drawings, making part of this specification, in which—

Figure 1 is a longitudinal vertical section, through the centre of a last, with its block secured thereto by means of my improved fastening.

Figure 2 is a transverse vertical section on the line $z z$ of fig. 1.

Figure 3 is a perspective view of the hook, which I employ for unlocking and removing the block from its last.

The ordinary method of securing the block of a last to the last proper, is by driving a tack or nail through the back of the upper side of the block into the last near the joint, or line, where their upper surfaces are brought together.

This method is objectionable for the following reasons:

The constant jarring, incident to punching the holes and driving the pegs into the sole, causes the fastening to become loose, and the block to be moved from its seat, so as frequently to require to be replaced and re-secured upon the last. Beside the loss of time incurred in this operation, and that required to withdraw the nail or tack, to allow the last to be removed from the boot or shoe, when the lasting is completed, both the block and last, by being continually pierced by the fastening, soon become split and broken, and are rendered worthless.

To remedy the above-mentioned difficulties, is the object of my invention, which consists in a spring-catch passing into a groove, and locking over a cross-bar, or other device for securing the block to the last, the catch being instantly liberated to allow of the removal of the block, by simply pressing a sliding pin against the catch, by applying the end of a suitably-formed "last-hook" thereto.

To enable others skilled in the art to understand and use my invention, I will proceed to describe the manner in which I have carried it out.

In the said drawings—

A is the body of the last or "last proper," and B, its block, both of the desired pattern.

Into the under side of the last, near the line a , where the upper surfaces of the block and last are united, is driven or screwed the bent end b of a flat piece of metal, the opposite extremity of which is provided with a hook, c , the piece of metal when so constructed and attached to the block B, serving as a spring-catch, C, the operation and purpose of which will now be explained.

d is a groove, formed in the upper surface of the body of the last, and extending from the line a cen-

trally, down to a point, e , the depth groove being sufficient for the front spring-catch therein.

Secured transversely over this groove d , under which the hook c rides and the spring-catch C enters the groove d , block upon the last.

The last is provided with a curve in its toe-portion, for the lower end of the nature of the block to rest on, by which the latter is prevented from moving laterally.

After the inner sole has been placed the block is secured thereto, as above held immovably thereon until the lasting is completed.

When the work is to be removed ordinary "last-hook," E, or "pull," bevelled down, (see fig. 3,) is employed to lock the block from its last:

A circular hole, i , passes transversely through block B, for the reception of the bevelled "last-hook."

From the bottom of this hole, and to its axis, extends a smaller circular projection of a cylindrical pin, k , which in the bottom of the pin resting upon the face of the spring-catch C, a little hook e.

By inserting the "last-hook," E, and pressing the bevelled end h of the pin k , the spring-catch C is depressed out of contact with the cross-bar, the block is then free to be drawn by the its position on the last.

It is evident, that instead of securing the catch to the block B, it may be attached to the last, in which case, the groove d would be formed in the block B for its reception, and the cylindrical pin k be made in the last, from the spirit of my invention.

By the application of my improved device, the block may be secured firmly in place upon its last, and removed in a ready and convenient manner, without injury to either the last or block.

Claim.

What I claim as my invention, an improvement, by Letters Patent, is—

The spring-catch C, and the last-hook E, so combined and operated as herein described, for securing the block B to its last A.

AMOS W. MERRITT.
